UNITED STATES PATENT OFFICE.

HENRY K. HESS, OF SYRACUSE, NEW YORK.

TONE REGULATOR FOR PHONOGRAHS.

Application filed October 18, 1921. Serial No. 508,430.

To all whom it may concern:

Be it known that I, HENRY K. HESS, a citizen of the United States, and a resident of Syracuse, in the county of Onondaga and 5 State of New York, have invented a certain new and useful Tone Regulator for Phonographs, of which the following is a specification.

This invention relates to phonographs, 10 and has for its object a tone modifier or regulator which is actuated by the motor of the machine, and which may, if desired, be disconnected from the motor and set in any desired fixed position.

15 The invention consists in the novel features and in the combinations and constructions.

In describing this invention, reference is had to the accompanying drawings in which 20 like characters designate corresponding parts in all the views.

Figure 1 is a vertical sectional view of a phonograph embodying my invention.

Figure 2 is a plan view of the regulator 25 and contiguous parts.

Figure 3 is an enlarged fragmentary sectional view of the connections between the regulator and the motor and also of the means for connecting and disconnecting the 30 regulator from the motor.

I have here shown my invention as embodied in the conventional cabinet type of phonograph.

1 designates the cabinet having the usual horizontal wall or partition 2.

35 3 is a record support which is here shown as a turntable.

4 is the motor suitably supported in the cabinet below the wall 2. 5 is the motor shaft extending upwardly through the wall 40 2 and on the upper end of which the record support, the turntable 3 is mounted.

6 is a tone arm. 7 is the reproducer and 45 8 the sound conduit which is in registration with the tone arm. 9 is the amplifier.

The tone modifier or regulating means 50 comprises a member movable transversely through the sound conduit and having a full portion to cut off the sound conduit, and an opening arranged to be brought during movement of the said member into and 55 out of registration with the passage of the sound conduit 8, and connections between said member and the motor or the shaft 5 thereof, and also means for connecting and disconnecting such connections from the

shaft 5. The cut-off or regulator member as here illustrated, is a rotatable disk 10 mounted on an axle 11 journaled in a suitable bearing 12 located outside of the sound conduit 8.

The portion of the disk 10 on one side of the axis extends transversely through the sound conduit 8 and is formed with an opening as an arc-shaped slot 13, arranged to be brought successively into and out of registration with the passage of the sound conduit 8 during rotation of the disk 10, the sound conduit being formed with a slot 14 to permit the passage of the disk.

The means for actuating the disk 10 in 70 the illustrated form of my invention comprises a gear 15 mounted on the motor shaft 5 and meshing with the toothed periphery of the disk 10. The gear 15 is normally disconnected from the shaft 5 and is connectable thereto to rotate therewith by a shiftable clutch section 16 mounted on the shaft and having a clutch face 17 coacting with the clutch face 18 on the opposing face of the gear 15. The gear 15 is here 75 shown as supported by a bracket 19 secured to the lower side of the wall 2 and having inturned flanges 20 extending into an annular groove 21 on the hub of the gear 15.

The clutch section 16 is keyed to the 80 shaft 5 in any suitable manner as by a pin 22 extending transversely through a slot 23 in the shaft 5. Said clutch section is shiftable by operating means preferably extending to the outside.

This operating means includes a rod 24 85 extending to the outside of the cabinet 1 and having a handle 25 at its outer end and being connected at its inner end to one arm of a shifting lever as a bell crank 26, the other arm of which is provided 90 with a fork working in an annular groove 27 in the clutch section 16.

The clutch section is held in its "off" and "on" positions by means of a spring pressed poppet 28 coacting with sockets 29 in 100 the periphery of the shaft 5.

The disk 10 is provided with indicators as the words "closed", "open" which come into registration with a sight opening 30 in the wall and indicate the position of 105 the slot 13 of the disk relatively to the passage of the sound conduit so that the disk 10 can be temporarily set to fully close, fully open, or partly close the passage of the conduit 8 to any degree.

110

In operation, when the clutch section is shifted to engage the clutch face of the gear 15, the cut off or regulating member 10 will be rotated slowly and alternately 5 bring the slot 13 into and out of registration with the sound conduit 8, thus gradually increasing the sound as the disk 10 rotates to fully open the passage 8 and decreasing the sound as the slot moves out 10 of registration with the passage 8 and the full part of the disk moves through the sound conduit. This operation breaks the monotony of the music.

The tone regulator member 10 may temporarily 15 be set at any desired position either to fully close the sound conduit 8 or fully or partly open it by shifting the clutch 17 into engagement with the clutch of the wheel 15 and permitting the motor 20 to run until the member 10 is in the desired position relatively to the sound conduit as indicated in the sight opening 30 in the top 2.

What I claim is:—

1. In a phonograph, the combination with 25 a rotatable record support, a motor for actuating the support, and a sound conduit, of a tone regulator coacting with the sound conduit, and connections between the tone 30 regulator and the motor whereby the tone regulator is actuated by the motor, substantially as and for the purpose described.

2. In a phonograph, the combination with a rotatable record support, a motor for actuating the support, and a sound conduit, 35 of a tone regulator coacting with the sound conduit, connections between the tone regulator and the motor whereby the tone regulator is actuated by the motor, and means for connecting and disconnecting the tone 40 regulator to the motor, substantially as and for the purpose specified.

3. In a phonograph, the combination with a cabinet having a horizontal wall, a record support rotatable above said wall, a 45 sound conduit depending from the wall, a tone arm mounted above the wall and connected to the sound conduit, of a tone regulator comprising a disk arranged to pass transversely through the sound conduit below the wall, the disk having an opening 50 arranged to be brought into and out of alignment with the sound conduit, the disk having indicators on the top side thereof showing the relative position of the opening of the disk and the passage of the conduit, and the wall having a sight opening 55 in line with said indicator, substantially as and for the purpose described.

In testimony whereof, I have hereunto signed my name, at Syracuse, in the county of Onondaga, and State of New York, this 11th day of October, 1921.

HENRY K. HESS.
